UNITED STATES PATENT OFFICE.

ROBERT GREENBURY CLAYTON, OF NEAR CHICAGO, ASSIGNOR OF ONE-HALF
TO R. G. HILL, OF LEBANON, KENTUCKY; A. K. RUSSELL ADMINISTRATOR
OF SAID CLAYTON, DECEASED.

ROCKING-CHAIR.

SPECIFICATION forming part of Letters Patent No. 335,428, dated February 2, 1886.

Application filed February 18, 1884. Serial No. 133,250. (No model.)

To all whom it may concern:

Be it known that I, ROBERT G. CLAYTON, a citizen of the United States, residing near Chicago, in the county of Marion and State of Kentucky, have invented a new and useful 5 Rocking-Chair, of which the following is a specification.

My invention relates to rocking-chairs; and it consists in the novel construction, adaptation, and application to each other of a pair of bent runners extending from the rockers upwardly and backwardly, and the seat, back, rockers, upper rounds, foot-rounds, and the several sets of braces, as will be hereinafter 15 more fully set forth.

In the drawings, Figure 1 is a perspective view of my improved chair; and Fig. 2 is a side elevation of that portion of the chair technically termed the "runner."

20 To the runners A A, which extend from rockers B B to top rounds, C C, is securely attached, by small wooden pins or equivalent device, the outer seat-frame, D. To the inner edges of this outer seat-frame is rigidly attached, in any well-known manner, an inner frame, E, constructed of flat pieces of wood, from the inner edges of which is stretched the seat proper, F, constructed of cane, canvas, 25 listing, or other strong but pliable material.

30 The runners A A, provided near their upper end with a bend, as at a, (by means of which the top portion of the chair-back is projected in a forward direction,) extend from the forward end of the rockers upwardly and 35 backwardly at such an angle in respect to the plane occupied by the seat as to provide the easiest and most comfortable angle to the back frame, G, which is securely attached at its lower end to the rear cross-piece of the 40 outer seat-frame, D, and at its upper end to the cross-round C. Slats g g, or surface constructed of material similar to that used in the construction of the chair-seat, complete the formation of the chair-back.

45 The lower ends of the runners are connected together by means of a foot-round, H. This foot-round, connected to the front cross-piece of the outer seat-frame by vertical brace-rods I I, forms a strong support for the front portion

50 of the seat. The rear portion of the rockers B B is securely attached to the rear portion of the outer seat-frame by means of strong braces or supports J J, which in turn are attached to each other by a round, K, as shown in Fig. 1.

55 Arms L L are provided, and are attached at their rear end to the back frame, G, at or near their center to the runner A A, and at their forward end, through the medium of uprights 60 l l, to the front portion of the outer seat-frame.

65 It will be observed that the various parts described herein are all interdependent, interbracing and interlocking, the seat being immediately or immediately (through the instrumentality of brace-rods) connected in a rigid 70 manner to all its surrounding parts, consisting of runners, rockers, back, and arms; the runners in the same manner to the seat, rockers, back, and arms; the rockers to the runners, 75 seat, back, and arms; the back to the seat, runners, rockers, and arms, and the arms to the back, seat, runners, and rockers.

80 The pieces from which my improved chair is constructed (with the exception of the flat inside seat-frame and rockers) are preferably 75 made of turned sugar-tree wood, the ends thereof being tightly interlocked in their respective sockets by reason of their interbracing character in such a manner as to prevent all "squeaking," and obviate the necessity 80 for gluing the parts together.

Having thus fully described my invention, what I claim as new, and desire to secure by Letters Patent, is—

85 In a rocking-chair, the runners provided near their upper end with a bend and extending from the rockers upwardly and backwardly, as described, in combination with the seat, the back, the rockers, the upper rounds, the foot-rounds, and the braces I and J, as and for the 90 purposes specified.

ROBERT GREENBURY + CLAYTON. [L. S.]
his
mark.
